UNITED STATES PATENT OFFICE

2,556,362

KNOCKDOWN PORTABLE TABLE

William S. Crumpler, Clinton, N. C.

Application November 14, 1947, Serial No. 785,953

3 Claims. (Cl. 311—89)

1

This invention relates to an improved construction of portable table especially adapted for outdoor use and which comprises a plurality of units detachably connected together and each composed of demountable sections including a table top formed of nesting leaves, to thus produce a multiple table structure of extremely simple construction capable of being stored in a limited space when not in use and which may be readily transported in a demounted condition.

Another object of the invention is to provide a table which will afford a maximum of usable space yet which will be extremely light in weight and durable.

Still a further object of the invention is to provide a table having supporting means capable of being readily imbedded in the ground or removed therefrom and which will function to support the table with a maximum of stability.

Still another object of the invention is to provide a table structure wherein a number of table units may be connected in spaced relationship and whereby each of said table units will tend to stabilize the other units and wherein the connecting elements therebetween will afford additional supporting surfaces for utility in conjunction with the table units.

Various other objects and advantages of the invention will hereinafter become more fully apparent from the following description of the drawings, illustrating a presently preferred embodiment thereof, and wherein:

Figure 1 is a top plan view showing the assembled table formed of two table units;

Figure 2 is a side elevational view thereof;

Figure 3 is a fragmentary perspective view of the table and illustrating a secondary use thereof;

Figure 4 is an enlarged vertical sectional view, partly in side elevation, of the central portion of one of the table units, and

Figure 5 shows the table top of one of the table units nested and with the connecting element disposed thereon.

Referring more specifically to the drawings, the improved portable nesting table constituting the invention is designated generally 7 and is shown as being composed of two corresponding table units, each designated generally 8 and which are detachably connected together by a connecting element 9.

Each table unit 8 includes a table top, designated generally 10 and composed of three leaves 11, 12 and 13 of substantially the same length and width and each of which is preferably provided with opposite recessed side edge portions

2

14, intermediate of the ends thereof and with a centrally disposed opening 15. The upper surface of the uppermost leaf 13 is recessed or provided with a countersink 16 around the opening 15 thereof and said aligned openings are adapted to receive the tubular shank 17 of a fastening element, designated generally 18, which extends downwardly therethrough and which is provided with an annular flange at the upper end thereof forming a head 19 which seats in the recess or countersink 16. The lower end of the shank 17 projects from the underside of the bottom leaf 11 and is externally threaded, as seen at 20 to receive a nut, designated generally 21, which is preferably in the form of a T-shaped coupling the intermediate socket portion 22 of which is internally threaded to receive the threaded end 20. A washer 23 is disposed between said portion 22 and the underside of the bottom leaf 11 and it will be readily apparent that the nut 21 can be tightened for clamping the leaves 11, 12 and 13 either in a nested position, one above the other as illustrated in Figure 5, or in a spread or extended position as illustrated in Figures 1 and 3, and by loosening the nut 21 the leaves may be rotated for positioning them in either a nested position or an extended position.

The portion of the T-shaped nut 21, opposite to the intermediate socket 22 is provided with an opening 24 of substantially the same diameter as the threaded bore of the socket 22 for removably receiving therein the upper end of a post 25 having a restricted shank portion 26 which projects from said upper end rotatably into the bore of the tubular stem 17 and so that the upper end of said post will define a shoulder around the shank 26 and which is adapted to bear against the lower end of the stem 17. The post 25 is also rotatably and slideably disposed in the opening 24 so that said post can be rotated relatively to the fastening 18, 21. As best seen in Figures 2 and 3, the lower end of the post 25 is provided with a tapered threaded terminal 27 by means of which the lower end of the post may be driven into the ground by exerting a downward pressure thereon while at the same time rotating the post. To facilitate this operation, a rod 28 extends diametrically through the post 25, below the nut 21 and has its ends protruding substantially therefrom and forming handles by means of which a downward and torsional pressure may be applied manually on the post 25 for anchoring it in the ground.

As seen in Figures 1 and 2, two of the table units 8 are shown assembled and in extended posi-

tions and it will be noted that the bottom leaves 11 thereof are each provided, preferably adjacent each end thereof, with a pair of transversely spaced openings 29. The connecting element or leaf 9 is provided adjacent each end thereof with similarly located bolts or pins 30 and is adapted to be positioned with its ends resting on the adjacent ends of the bottom leaves 11 of the two table units 8 and with the bolts or pins 30 thereof depending into the openings 29 of said ends of the leaves 11 for detachably connecting the leaves 11 rigidly in spaced relationship. It will likewise be readily apparent that an additional unit 8 could be connected by another attaching leaf 9 at the opposite end of either of the bottom leaves 11 in the same manner, so that the table 7 could be composed of two, three or more table units 8. As clearly illustrated in Figure 1, the ends of the leaves 11, 12 and 13 are preferably convexly rounded and the ends of the connecting leaf 9 are preferably concavely rounded.

The connecting leaf 9 is preferably provided with spaced openings 32 which are arranged a distance apart equal to one third the distance between the posts 25 so that the leaf 9 may be initially used as a layout member for marking off the proper spacing between the posts 25, after which said posts may be driven into the ground, as previously described, and the table tops 10 thereafter placed thereon and the leaves 12 and 13 then extended. The bottom leaves 11 are subsequently connected by the leaf 9, as previously described, thus enabling the table 7 to be readily set up by one person.

The outer ends of the bottom leaves 11 and both ends of the leaves 12 and 13 may be utilized with a place setting so that five persons may sit at each of the table units 8 and the leaf 9 may also be utilized for seating additional persons at the table 7 or for supporting a portable cooking stove.

The top leaf 13 of each table unit 10 has four openings or recesses 31, as seen in Figure 1, which are properly spaced to receive the pins or bolts 30 when the leaf 9 is stacked thereon, as seen in Figure 5.

As best seen in Figure 2, the legs 25 are formed of upper and lower sections 33 and 34 and the upper section has a restricted depending extension 35 that is threaded to fit an upwardly opening threaded socket 36 of the section 34 for detachably connecting the sections to permit their dismantling for more convenient storage.

The upper section 33 is of sufficient length so that it can be threaded into a socket 37 of a cross-shaped base 38, by the use of a pair of which bases 38 the table units 10 may be erected indoors or on a concrete or other solid outdoor surface.

The leg 25 can be used outdoors by being driven into the ground and with the folded table top as a seat or a folding table of smaller size may be employed in this manner.

Various modifications and changes are contemplated and may obviously be resorted to, without departing from the spirit or scope of the invention as hereinafter defined by the appended claims.

I claim as my invention:

1. A demountable table comprising a plurality of table units each including a table top formed of a plurality of superposed leaves, adjustable means extending through the central portions of said leaves for rotatably connecting said leaves whereby the leaves may be positioned in either an extended position or a nested position relatively to one another, said means being adjustable for clamping the leaves in either of said positions, a post forming a part of each table unit and having one end to be driven into the ground for anchoring said post in an upright position, said means constructed for detachably receiving the opposite, upper end of the post for demountably supporting the table top thereon, a connecting leaf extending between adjacently disposed ends of the bottom leaves of two of said table units, and means for detachably connecting the ends of said connecting leaf to the adjacent ends of said bottom leaves.

2. A table as in claim 1, said means comprising a tubular stem extending rotatably through the central portions of said leaves and having a headed upper end countersunk in the upper leaf and an externally threaded lower end extending below the bottom leaf, a clamping nut for engaging the externally threaded end of said tubular shank for cooperation with the head thereof for releasably clamping the leaves, and said post having a restricted upper end extending detachably into said tubular shank and providing an upwardly facing shoulder on which the lower end of said shank rests.

3. A table as in claim 1, said connecting leaf having openings spaced apart a predetermined distance relatively to the effective lengths of the bottom leaves and connecting leaf for measuring the distance between the posts of the table units whereby said posts may be initially erected in properly spaced relationship for subsequent application of the connected table tops thereto.

WILLIAM S. CRUMPLER.
